UNITED STATES PATENT OFFICE

152,112

DESIGN FOR A BOOK END

Albert W. McGowen, Boulder, Colo.

Application April 7, 1947, Serial No. 138,212

Term of patent 14 years

(Cl. D33—1)

To all whom it may concern:

Be it known that I, Albert W. McGowen, a citizen of the United States of America, residing at Boulder, in the county of Boulder and State of Colorado, have invented a new, original, and ornamental Design for a Book End, of which the following is a specification, reference being had to the accompanying drawing, forming a part thereof.

In the drawing,

I claim:

The ornamental design for a book end, as shown.

ALBERT W. McGOWEN.
